UNITED STATES PATENT OFFICE.

LUDWIG GUTMANN, OF FORT WAYNE, INDIANA.

ELECTRIC-RAILWAY SYSTEM.

SPECIFICATION forming part of Letters Patent No. 423,552, dated March 18, 1890.

Application filed February 18, 1889. Serial No. 300,235. (No model.)

To all whom it may concern:

Be it known that I, LUDWIG GUTMANN, a subject of the Emperor of Germany, and a resident of Fort Wayne, in the county of Allen 5 and State of Indiana, have invented certain new and useful Improvements in Electric-Railway Systems, (Case 25,) of which the following is a specification.

This railway system has for its purpose to 10 distribute safely and economically electric energy over large distances, and is such a system in which high-tension currents are used in combination with converters. The organization embraces one or more generators 15 producing alternating, pulsating, or intermittent currents of constant potential, each having their independent feeder-circuits provided with switches or other means for connecting two or more feeders to one genera- 20 tor, converters permanently connected with their primary coils to said feeder-circuits in multiple arc, and the secondary coils of the said converters left normally open and only closed by moving translating devices, such 25 as electric motors on cars, said motor automatically connecting the secondary coil of the nearest converter to the work-line and disconnecting the converter which last supplied it with current. By this system I do 30 not use more converters than necessary and each only for a brief time, thereby increasing the life of such apparatus, reducing the strain on the insulation, and (as not all converters are doing work but only a portion) it 35 will be evident that the power supplied will be very nearly proportional to that consumed; further, the amount of leakage is minimized, and, lastly, I may use a much smaller conductor for the work-circuit than 40 otherwise would be required, because the motor is always supplied by the nearest converter and because there is practically but very little loss in conveying the electric energy a short distance. This construction is 45 equally applicable to a system having either both the conductors overhead or one overhead and the other underground, or both underground.

The drawings accompanying this applica- 50 tion represent the details of the complete system applied to underground conductors.

Figure 1 is a diagram showing the principle involved and some of the stationary apparatus and the electric circuits. Fig. 2 is a diagram embodying the principle and showing transmitting devices in circuit. Fig. 3 shows a sectional view of a conduit and preferred means of conducting the current to the motor. Fig. 3^a shows abnormal position of apparatus in Fig. 3. Figs. 4, 5, 6, 7, and 55 60 7^a are detailed views of Fig. 3. Figs. 8 and 9 are modifications of Fig. 3. Figs. 10, 11, and 11^a are detailed views of Figs. 8 and 9. Fig. 12 shows a current-collector adapted for an underground system. Figs. 13 and 14 are 65 diagrams of circuits to illustrate electrical distribution applicable to apparatus shown in Figs. 3 to 12, inclusive. Figs. 15 and 16 are front and side views of a portion of Fig. 2 on an enlarged scale. 70

Referring to Figs. 1 and 2, A are alternating, pulsating, or intermittent current-generators; B, the main feeders connected thereto; C, local converters connected in multiple arc to the feeders; D D', secondary or work circuits of the converters; E E', main feeder-switches; F, posts or conductor-supports for all feeders; G G', open-circuit secondary terminals; H, double-pole switch; I, pivot-joint; K, lever-cam; L, contact-terminals of local 80 battery-circuit; I', insulator joining switches H; M, car with motor; N, tripping device on car; O, local battery for energizing electro-magnet T; P, primary coils of converters; R, rheostat for field-magnets of generators A; 85 S, secondary coils of converters; T, electro-magnet; U, armature of said electro-magnet and attached to switches H; V, cross-arm on the said posts for feeder-circuits, (primary;) W, work-circuit cross-arms; X, trolley or cur- 90 rent collector on secondary conductors; Y, exciter for generators A. 95

Referring to Figs. 3, 4, 5, 6, 7, 8, 9, 10, 11, 12, 13, and 14, a is a vertically-movable rail used as a conductor; b, insulation on each 100 side of said rail; c and d, side plates of the conduit; e, base-plate of the conduit; f, work-circuit closer; f', projecting lever attached to said circuit-closer; g, guide projections for movable rail a; g', projections for fixing and supporting the sides c and d in base-plate e; g'', holes in base-plate e for the reception of

projections g' ; h , terminal-blocks of conductor i ; i , main conductor; k , main-conductor supporting-groove; l , insulation for switch supporting the circuit-closer f ; l' , insulating-block on side d ; m , draining-groove in conduit; n , foundation-bolts; o , cement or concrete, wood, or other foundation for such plates; p , rails of track; r , insulation for supporting main-wire terminals; s , secondary-circuit contact-blocks; t , support for lever of circuit-closer; u , projection upon support t ; v , arrester for lever of circuit-closer and guide for movable rail; w , supporting-springs for movable rail; x , contact-wheel of a current-collector, and y , scraper of conducting-rail and protector-brush z .

In Fig. 1, A represents two alternating, pulsating, or intermittent current dynamos, each having an independent main or feeder circuit B, and provided with circuit-closers E to enable more than one feeder to be connected to the same generator. Converters C are distributed all over the circuit and connected to circuit B in multiple arc. The primary coils are shown constantly closed, while the secondary coils are shown normally open. One end of the secondary coil S is connected to the work-circuit D', while the other end is connected to circuit D, which is shown interrupted at terminals G. The secondary wire is provided at terminals G with contact-blocks operated by the passing car, as shown in Fig. 2, so as to connect them to terminals G'. The generator A is excited by dynamo Y, the strength of which can be regulated by rheostat R. The currents developed by generators A circulate through the line one side of B, the primary coils of converters C, the other side of line B, and back to dynamo. The feeder-circuits B are shown supported on cross-arms V of poles F. The ends of the secondary coils are connected to D and D', but both wires of each coil are interrupted at G. The terminals G may be closed by switches H, operated by lever K and pivot-joint I.

O is a battery or other generator adapted to energize electro-magnet T. The armature U of magnet T is firmly connected to switch-lever H, one battery-pole being joined to magnet T and the other to L, a contact-terminal of the battery lying in the path of the car M. The free end of the coil of magnet T is connected to a second point L of said battery. Both contact-points L can be connected momentarily by projection N coming between them.

The action is as follows: The secondary circuits of converters 1 and 3 are shown open, while that of 2, on which the car is traveling, is closed. On passing converter 1 the projection N forces down the lever K, which on turning to the right moves circuit-closers H of converter 1 by aid of universal joint I, thereby closing the secondary circuit. It then travels beyond converter 2, the middle lever K having been moved by projection N, as

shown. The pivot-joint I" is moved also, and operates the switch H, thereby closing the secondary circuit of converter 2. A moment later projection N comes in contact with L, a terminal of a local circuit in connection with circuit-closer of converter 1. By connecting the two points L the local circuit is closed and the electro-magnet T is energized and attracts its armature U, thereby taking or moving circuit-closers H from contact-blocks G, and thereby opening the secondary circuit of converter 1. As the car advances it will close the circuit-closer of converter 3, and afterward open circuit-closer of converter 2 by making connection at terminals L. In the third converter the electro-magnet and battery are omitted for sake of clearness.

In Fig. 3 a is an independent rail placed between the track-rails p. In this sectional view the rail rests partly on the spring f or circuit-closers and partly on springs w, omitted here to preserve clearness, but shown in Fig. 4. The springs w are helical springs loosely surrounding the projections g.

Fig. 4 shows the rail a and circuit-closers f at right angles to the view, Fig. 3. Springs w and circuit-closers f rest on insulation l, which may consist of creosoted wood, tarred wood, porcelain, or any other suitable insulator. Circuit-closers f and springs w combined assist each other in maintaining the rail a vertically upward. The conduit is formed by rail a, side pieces c and d, and base e, the whole resting in a foundation o, of concrete, cement, wood, or other suitable material.

o forms a rectangular or similar channel provided with grooves m for carrying off any water, grit, or dirt that may drop into the conduit. In this channel is placed a base-plate e, which may be of cast-iron, wood, or other suitable material. The whole length of the conduit is supplied with such base-plates e of comparatively short length, each plate being bolted to the foundation by bolts n. The plate ends have a miter, so that one plate overlaps the other, as shown in Fig. 7 and Fig. 7^a, the latter representing a side view of the plates, while Fig. 7 is a view from the top. Base-plates e are provided with holes g'', Fig. 6, to receive the lugs or projections of the angular side pieces c and d. In the center of base-plate e is mounted the above-mentioned insulator l, circuit-closers f, springs w, and movable rail a. The left-hand side of the conduit is occupied by the rectangular piece c being lodged in the plate e by means of projections or lugs g'. c is provided with a projection containing a groove k, in which the well-insulated main conductor i is located, the latter being connected to contact-blocks h, and said blocks being separated from side plate c by interposed insulation r. The one end of a secondary conductor S passes through the foundation and plate c to special blocks s, Fig. 5. This figure shows the angular piece c in a position at right angles from

that of Fig. 3. The secondary wire penetrates the plate *c*, and is connected to *s*, which are contact blocks or terminals mounted on the insulation *r* and distributed between every alternate pair of blocks *h*, which are the terminals of the main conductor *i*, which rests in the groove *k*.

In Figs. 3 and 5 the projections *g*' are more clearly shown. The angular side piece *d* is similar to *c* and is fixed on or is resting on the plate *e* in the same manner as *c*. The side plate *d* is not required for opening or closing of any circuit, and it is therefore not provided with a conductor or contact-blocks.

15 To prevent too great expansion of the ends of spring *f*, the side *d* is provided with an insulating-block *l*'.

In the normal condition of the system the primary coils are closed, as shown in Figs. 1 and 2, but the secondary coils are open, the latter being closed by circuit-closers operated by the moving train. These circuit-closers are *f*.

Fig. 3 shows the apparatus in the normal condition of the system, being open at terminal *h*; but should a train or car provided with a projection—such as a fifth-wheel *x*—depress the rail *a*, then it will occupy the position indicated in Fig. 3^a, forcing the ends of *f* apart, which rest on one side on contact-blocks *h* *s*, completing the circuit from conductor *s* to conductor *a*. On the other side, against block *l*', no circuit is closed. The secondary circuit being closed, causes the current to flow from conductor *S*, contact-blocks *s* and *h*, circuit-closers *f*, rail *a*, to motor exciting-coils, and from motor in the reverse order to the other pole of the converter-coil. The rail *a* is insulated from *c* and *d* by insulation *b*, attached to either side of *a*. As soon as the pressure ceases *a* will be forced up by springs *w*, and the secondary circuit will be open again. The slot between *c* and *d* is filled and protected by rail *a*, which in Fig. 3 has a T-shaped cross-section and prevents the falling of dirt into the conduit. By this construction (everything being movable) any obstacle can easily be removed and the whole system can quickly be inspected simply by lifting out the rails *a* and, if necessary, the angular piece *d*.

Figs. 8, 9, 10, and 11 represent a modification of Fig. 3.

In Fig. 8 everything is the same as in Fig. 3, with exception of the modified form of rail *a* and circuit-closer *f*. The cross-sectional shape of *a* is that of an arrow. It is forced upward by spring *w* and closes the aperture between *c* and *d*, slightly projecting over the surface.

Fig. 10 is a view of rail *a* at right angles to that of Fig. 8. *a* is provided with the same projections and tension-springs as in Fig. 4. The rail having to operate the levers *f*' of the circuit-closers *f* is provided with holes for the location and passage of lever *f*', Figs. 8, 9, 10, and 11.

In Fig. 8 blocks *h* are placed in a more protected position, and circuit-closer *f* is supported by standards *t*.

In Figs. 8, 9, and 11 the projection *u* on standard *t* serves as a guide for the rail *a*; so does block *v*, Figs. 8, 9, and 10, which in addition is intended to prevent too great a strain on circuit-closer *f*, which, if depressed, rests on projection *v* as to the lever *f*'. To make these rails completely safe, I prefer to so adjust the levers *f*' that contact will only then be established when the projecting point of rail *a* is slightly below the top surface of side plates *c* and *d*, Fig. 9, so that when both conductors are placed side by side and both rails should be pressed down simultaneously by a car or a horse placing the rails level with the surface the circuit is not completed, and consequently no shocks experienced.

Fig. 9 shows the circuit completed when the contact-wheel *x* or brush *z* or any other suitable apparatus designed for the purpose depresses the rail *a* below the surface. The electrical connections of Fig. 8 are the same as in Fig. 5. It will be noticed that in the normal condition of the system the secondary circuit is open and the conduit is closed by rail *a*, while when occupied by a car or train the wheel *x* depresses the rail *a* for a short time and closes the secondary circuit, which is opened again as soon as the car has passed the said rail. The rail *a* has been provided at the highest part with a dull knife-edge to prevent anything from resting on it, and to oppose any formation of ice or the like on the contact-surface.

Fig. 11 shows a view from the top on the circuit-closer *f*, lever *f*', and the support *t*, on which they are movably mounted, also the relative position of the movable rail *a* to the lever *f*'.

Fig. 11^a shows a perspective view of circuit-closer *f* and lever *f*' on an enlarged scale.

Fig. 12 represents the contact-maker, consisting of wheel *x*, which is for the purpose of acting with pressure on rail *a*.

y is a fork or scraper to protect brush *z*, and to procure a good clean surface on contact-rail *a* for the brush *z* placed behind it.

I claim as my invention—

1. In an electric-railway system, the combination of one or more generating stations for generating alternating, pulsating, or intermittent currents, each having independent main-line feeders extending therefrom, and to within close proximity of one another, and connected at the points of approach by switches for interchanging the generators of one station with those of another, and converters connected to said feeders and distributed throughout the circuits of the feeders, the secondary coils of said converters being constructed to produce a uniform pressure throughout the secondary or work circuit.

2. In an electric-railway system, the combination of an alternating, pulsating, or intermittent current generator, feeder-circuits con-

1. nected thereto and to each other, electric converters whose primary coils are connected in multiple arc to said feeder-circuits, terminals to the secondary coils of said converters, electric cars provided with motors, a pair of terminals for each motor, one set of circuit-closers in a normally-open circuit with one terminal of each motor and one terminal of each secondary coil, and a second set of circuit-closers in a normally-open circuit with the remaining terminal of each motor and one terminal of each converter and rigid connections, such as rods connecting in pairs the said circuit-closers.
2. In an electric-railway system, the combination of generators of alternating, pulsating, or intermittent currents, each having independent main feeders, means for connecting the feeders to the same generator, electric converters connected with their primary coils to said feeders, and having their secondary coils connected to a common pair of conductors and having their secondary coils normally open, and electric cars in circuit with the said pair of conductors.
3. In an electric-railway system, the combination of generators of alternating, pulsating, or intermittent currents, feeder-circuits connected to each generator, means such as switches E and E' connecting the feeders of different generators, as and for the purpose set forth, and converters connected with their primaries to the said feeders and having their secondary conductors all connected to a common pair of supply-conductors D and D', the said secondary conductors being normally open and provided with circuit-closers, and

electric cars in electric contact with the said supply-conductors.

4. In an electric-railway system, the combination of generators of alternating, pulsating, or intermittent currents, independent feeder-circuits for said generators, circuit-closers connecting the said feeder-circuits to one another, electric converters having their primary conductors in circuit with the feeder-circuits and their secondary conductors provided with automatic circuit-closers normally open, supply-conductors D and D' in circuit with said circuit-closers, cars provided with electric motors in traveling contact with the said supply-conductors, and operating-levers to said circuit-closers and in the path of said cars.

5. In an electric-railway system, the combination of an alternating, pulsating, or intermittent current generator in circuit with the primary circuit of an electric generator, and secondary coils of the converter connected to electric contact-conductors common to all said secondary coils, and electric cars provided with electric circuit-closers which are in circuit with the said electric contact-conductors and with said secondary coils, the circuit which has the circuit-closers being normally open.

In testimony that I claim the foregoing as my invention I have signed my name, in presence of two witnesses, this 4th day of February, 1889.

LUDWIG GUTMANN.
